UNITED STATES PATENT OFFICE.

VICTOR ANGERER, OF RIDLEY PARK, PENNSYLVANIA, ASSIGNOR TO WILLIAM WHARTON, JR., & COMPANY, INCORPORATED, OF PHILADELPHIA, PENNSYLVANIA, A CORPORATION OF PENNSYLVANIA.

TONGUE-SWITCH.

No. 881,043.

Specification of Letters Patent. Patented March 3, 1908.

Application filed November 27, 1907. Serial No. 404,094.

To all whom it may concern:

Be it known that I, VICTOR ANGERER, a citizen of the United States, residing in Ridley Park, Pennsylvania, have invented certain Improvements in Tongue-Switches, of which the following is a specification.

The object of my invention is to so arrange a pivoted tongue switch that the bearing for the pivot of the tongue can be readily removed or adjusted as desired, and yet when in a fixed position will remain perfectly rigid under all conditions. This object I attain in the following manner, reference being had to the accompanying drawing, in which:—

15 Figure 1, is a plan view of a pivoted tongue switch to which my invention is applied; Fig. 2, is a sectional view on the line 2—2, Fig. 3, illustrating my invention; Fig. 4, is a section on the line 3—3, Fig. 2; Fig. 5, is a 20 sectional view on the line 4—4, Fig. 2; Fig. 5, is a perspective view of the annular bearing; and Fig. 6, is a perspective view of the base plate.

25 A is the body of the switch structure made preferably of manganese steel. The body has projections a , a' and a'' to which the rails of the track are coupled in the ordinary manner.

30 B is the tongue of the switch adapted to be moved either against the rail flange c or the guard flange c' of the switch structure; this tongue B has a downwardly extending pivot b at its extreme rear end as indicated in Fig. 2.

In the body of the switch structure A is a 35 cavity C containing a base plate F and an annular bearing E for the pivot b of the switch tongue. The base plate F, which is preferably quadrangular in shape, as shown in Fig. 6, is slipped into place through a slot 40 in the rear wall of the cavity, and the bearing E is placed in position from above. The cavity is much larger than the annular bearing E so as to allow the bearing to be inserted in the cavity and then pushed under the 45 overhanging portion a^3 of the body A, Fig. 3.

When the body of the switch structure is made of manganese steel it is practically impossible to make a smooth finish for any part used as a bearing, owing to the hardness of 50 the metal, and by mounting the parts E and F within the switch structure I am enabled to provide a smooth surface for the pivot of the switch tongue. The annular bearing E can be adjusted and held in its adjusted position 55 by set screws i which are screwed into the cas-

ing surrounding the cavity and on these screws are locking nuts i' which hold them in position after adjustment. In order to provide a suitable seat for the base plate F, I pour molten metal, as indicated at x , between the plate and the bottom of the manganese casting and I also pour molten metal, as indicated at x' , between the annular bearing and the sides of the cavity, which will close the openings against the accumulation 60 of dirt and will hold the set screws rigidly in position. As there is considerable space in front of the bearing to allow of its withdrawal from under the overhanging portion a^3 , I usually place a block of metal I in this space to 65 act as a filler in place of the molten metal. When it is desired to remove the bearing E after it becomes worn or injured, I simply remove the metal x' and the block I, back off the set screws i and slide the bearing forward 70 until it is clear of the overhanging portion a^3 , when it can be readily removed and a new one substituted for it if desired. The annular bearing E is adjusted and held by the set 75 screws and it need not be adjusted again unless the parts become worn, or it is desired to remove the bearing. Thus it will be seen that I can make the body of the switch structure of hard metal, such as manganese steel, and have a neat fitting bearing for the switch 80 tongue so that no material can accumulate around the pivot of the switch tongue. The parts can be readily assembled and removed, as desired, and yet when in position will be 85 absolutely rigid.

90 I claim:—

1. The combination of a body portion of a switch structure, having a cavity, an annular bearing mounted in the cavity, set screws for adjusting the bearing, and a switch tongue 95 mounted in the bearing.

2. The combination in the body portion of a switch structure, having a cavity and a portion overhanging the cavity, of an annular bearing mounted in the cavity under the 100 overhanging portion, said cavity being of such a size that the bearing can be moved from under the cavity and withdrawn when desired, means for retaining the bearing in the cavity, and a switch tongue having a 105 pivot adapted to the bearing.

3. The combination of a body portion of a switch structure having a cavity therein open at the top and at the rear, a base plate adapted to be inserted in the cavity through the 110

opening in the rear, an annular bearing adapted to be inserted in the cavity from the top, means for retaining the bearing in position, and a switch tongue having a pivot adapted 5 to the bearing and resting upon the base plate.

4. The combination of a body portion of a switch structure, having a cavity therein, a base plate mounted in the bottom of the cavity, an annular bearing mounted upon the 10 base plate also within the cavity, set screws for adjusting the annular bearing within the cavity, and soft metal filling the interstices between the bearing and the plate and the body of the switch structure, with a tongue 15 having a pivot adapted to the bearing.

5. The combination of a body portion of a switch structure having a cavity at one end

and having a portion overhanging the cavity, an annular bearing mounted in the cavity and under the overhanging portion of the 20 body, means for adjusting the bearing in the cavity, a block inserted between the forward end of the bearing and the walls of the cavity, a base plate mounted under the bearing, and a switch tongue having a pivot mounted 25 in the bearing.

In testimony whereof, I have signed my name to this specification, in the presence of two subscribing witnesses.

VICTOR ANGERER.
